CLAIM

The ornamental design for a shoe upper, as shown and described.

DESCRIPTION

FIG. 1 is a front perspective view of a shoe upper showing my new design;

FIG. 2 is a medial side view thereof;

FIG. 3 is a lateral side view thereof;

FIG. 4 is front view thereof;

FIG. 5 is a rear view thereof; and,

FIG. 6 is a top view thereof.

The broken line showing of the bottom edge, the lace loops, and the remainder of the shoe upper is for illustrative purposes only and forms no part of the claimed design.
